CORD LINE CHALKER

Charles Scudder, Bayside, N. Y.

Application June 4, 1952, Serial No. 291,615

11 Claims. (Cl. 33—87)

1

This invention is concerned with new and useful improvements in cord line chalkers. It is particularly concerned with a cordline chalking device of a simple and practical nature employing powdered chalk as the chalking medium.

As we well know, chalked cord lines are used in various trades, particularly the construction trades. They are used primarily to quickly form lengthy lines of a temporary nature. Such lines serve as guides for excavations, painting of stripes, laying of walks and various other purposes. In most cases it is desired that the guide line be sharp and without fuzz to serve as an accurate guide, and that it further be solid so as to be clearly visible and of reasonable durability. It has been customary to chalk a cord line by drawing it over a cake of hard chalk or through powdered chalk. In the first case where hard chalk is used, the cord line is not thoroughly coated and the line produced by it is not full and is spotty with light, dark and vacant sections. In the case where powdered chalk is used by customary methods to chalk the line, the line produced is splotchy, not very durable, and serves as a poor guide for accurate work.

The use of powdered chalk for cord line chalking is preferable to hard chalk, as there is less waste, the hard chalk being quickly cut to small and useless pieces. On the other hand the use of powdered chalk has other disadvantages in that the chalk spills from its container, and for this reason it cannot be carried about in the pocket. Often in the chalking process it coats not only the cord line but the user as well.

Now, I have invented a cord line chalking device which employs powdered chalk and yet, does not have the disadvantages commonly associated with powdered chalk. It is capable of producing a chalked cord line of any length, quickly and of a nature that has all the qualities desired in a chalked line. My invention can be carried in the pocket without spilling its contents; it can be used without coating the user; it produces, when snapped in customary manner, a guide line that is clear, sharp and solid throughout without fuzz, without splotches and with lasting effect.

The article of my invention comprises a container of small and compact size in which there is well confined a supply of powdered chalk. Within, the container includes a rotary member that is freely rotatable when a cord line is drawn over it and through the container. The rotary member serves to stir up the chalk, and as the line is drawn over it the chalk is forced into the strands of the cord and over its surface. The de-

2

vice further includes wiping means which serves to wipe only the fuzz from the outer surface of the cord. The cord that issues from the container is well charged with chalk and its surface is free of fuzzy particles.

The general object of the invention is a practical and compact cord line chalking device that can be handled and carried about without spilling its contents, and which can produce a thoroughly chalked cord line free of fuzz.

A further object of the invention is a cord line chalker utilizing powdered chalk, which will enable quick chalking of a continuous line which, when snapped, will produce a sharp, well defined line impression that is both solid and long lasting.

The foregoing objects and advantages of this invention, as well as others, will become readily apparent as this specification unfolds in greater detail, and as it is read in conjunction with the accompanying drawings wherein a specific embodiment of the invention is illustrated.

In the drawings:

Fig. 1 is a perspective view of the invention that also indicates the manner of using it;

Fig. 2 is a diametrical cross section through the device;

Fig. 3 is a plan view of the rotary member; and

Fig. 4 is a view in perspective of one of the complementary shells.

Referring to the drawings for a detailed description of the invention, there is disclosed a container generally designated 1, adapted to hold therein a supply of powdered chalk 2, and comprising a pair of complementary shells 3, 4, engaged one to the other by a threaded post 5 of one shell threaded into an internally threaded shaft or cylindrical member 6 of the other shell. Both shells except for the members 5 and 6 are of identical structure.

Each shell is hat like in appearance, having a crown 9, a brim 10, and a circular well or recess 11 centrally of the shell. In each brim there is an annular trough in which is contained a flat band 12 of soft material, such as rubber. When shell 3 is threaded by its post 5 into the shaft 6 of the other, both shells are drawn together complementing one another. The complementary shells form a hollow space or chamber 14 within the container adapted to hold the powdered chalk supply. The bands of each shell contact one another when the shells are drawn together, as in Fig. 2, thereby preventing the escape of the chalk from the container. Within

the chamber 14 formed by the complementary shells there is adapted to rotate a wheel element 15 carried for rotatable movement upon an axle formed by the combination of the shaft 6 and the post 5. The circular member 15 is in the nature of a wheel or turbine, having a plurality of radial fins 16 which serve to stir the powdered chalk about the container as the wheel rotates. Each fin radiates from a central disc portion 17, and as each fin extends toward the circumference of the wheel, its shank as at 18 gradually twists from a plane coplanar with the central disc portion to a plane at the extremity of the fin which is at right angles to the plane of the disc portion; that is, a plane which is parallel with the axis of the wheel element. Each fin is provided at its extremity with an extended broad foot portion 19 having an arcuate surface which is concentric with the axis of the turbine or wheel element 15, as in Fig. 3.

The turbine member is adapted to be rotated by a cord line 20 drawn between the shells and over the peripheral surfaces of the several foot portions of the fins. As the turbine wheel rotates the twisted shanks of the fins serve in the manner of a screw to pick up and distribute the powdered chalk about the chamber 14 and between the surfaces of the fin feet and the opposite wall of the container so as to bring the chalk to the cord line.

It is to be noted that the shells are circular and that, when assembled together as in Fig. 1 a broad peripheral surface 21 is formed by the complementary flanged or brim portions 10. There is also provided an annular shoulder 22 between the crown and brim portions of each shell, and that the outer wall of each crown is flat as at 23. The device in this form has many advantages facilitating its use. When the device is being used, it is held in one hand and a cord line placed between the shells is drawn through it with the other hand to rotate the turbine member. The broad peripheral surface of the complementary brims enables the device to be comfortably palmed, while the flat outer walls 23 enable the device to be comfortably held between the ham of the thumb and the fingers, while the annular shoulders 22 enable the device to be easily gripped by the thumb and fingers, particularly when adjusting the relative positions of the shells to one another. This form of the device is designed to insure not only comfortable handling, but also a firm and easy grip that will not permit the device to slip from the hand during the chalking operation.

The peripheral surfaces of the fin feet 19 are provided with a plurality of scorings or lines as at 24 in Fig. 2. Because of these, the chalk stirred about by the rotary member 15 settles in the scorings and clings to and covers the surfaces of the fins. Further, as a cord line is simultaneously pressed against the fin feet and drawn over them to rotate the rotary member it also tends to grip the fins and rub through the powdered chalk. In this way chalk is thoroughly forced into the strands of the cord line.

It is also to be noted that the free end 25 of each fin foot extends forward and slightly downward, and is spaced a little to the rear of the fin next adjoining, so as to form a triangular space 26 between each fin. This space further serves in insuring a thoroughly chalked cord line. It can be seen that, as the device is palmed and the wheel member rotated by drawing the cord over it, chalk is picked up by the fins and thrown

about the container. It falls and accumulates in the spaces 26 between the fins, it also accumulates between the space 27 separating the fins from the opposite wall of the container. This insures a quantity of chalk above, on and about the peripheral surface of the fins, so that the cord line is drawn through the chalk and is insured a thorough coating on all sides. When the wheel is at rest the powdered chalk filters down through the spaces between the fins to settle in the container as in Fig. 2.

It can readily be appreciated that, when the cord line is pressed against the fin feet and pulled over them and between the shells, chalk will not only be rubbed well into the line, but it will also thoroughly coat the surface of the cord. Further, as the line is drawn out from between the shells it lightly contacts the opposing rubber surfaces 12 of the shells which wipe the fuzz from the line. It is desirable that shells do not press tightly against one another, but that they be adjusted together only to that extent where the cord line may freely pass between them and only lightly contact the bands 12. This will allow only the fuzz to be wiped from the cord line as it issues from the shells.

It can readily be seen now, that the chalked line that issues from the chalking device has all the qualities desired in a chalked line, and that a line impression formed by snapping the cord will be clear without blotches or fuzz, sharp and solid; it will be clearly visible, an accurate guide and long lasting.

Another feature of the invention which adds to its many advantages is the position of the wheel member 15 in the container. The wheel is centered on its shaft so that the mid-point of the peripheral surface of the fins is directly below the point of contact of the shells 3, 4 with one another. To insure this the wheel is provided with a hub 28 that extends equally from opposite faces of the wheel. The ends of the extended hub portions bear against shoulders 29 at the bases of the axial elements 5, 6. The advantage of centering the wheel member in this manner is to make certain that the cord line contacts the peripheral surfaces of the fins at all times without danger of slipping off at the sides and becoming entangled in the fin blades. When the device is in use the shells are preferably adjusted so that there is slight play between the hub extensions and the bearing shoulders 29 to prevent the wheel from binding.

In Fig. 4 it can be seen that the rubber strips 12 are raised slightly above the edges of the thin trough walls in which they are contained. This feature enables the shells to be drawn sufficiently together where the bands 12 press against one another, whereby the container is effectively sealed against the escape of chalk. Further, when in use the bands not only serve the purpose of wiping the fuzz from the cord line, but also prevent chalk from spilling from the device.

While I have described what I consider to be a highly desirable embodiment of my invention, it is plain that some changes in form could be made without departing from the spirit and scope of the invention, and I therefore do not limit myself to the form herein shown and described, nor to anything less than the whole of my invention as herein shown and set forth and as hereinafter claimed, and it is my intent to claim all that may reasonably be within the spirit and scope of the invention.

I claim:

1. A cord line chalking device comprising a circular container having a chamber adapted to hold a supply of powdered chalk, the container including a pair of opposed complementary circular shells, an adjustable axial element joining the opposed shells together, the shells being adjusted in relation to one another to permit a cord line to be freely drawn between them, a rotary member carried within the chamber for rotatable movement on the axial member and including a plurality of fins adapted to distribute the powdered chalk about the chamber for contact with the cord line during rotation, and peripheral extensions on the fins adapted for contact with the moving cord line whereby the rotary member is adapted to be rotated.

2. A chalking device as in claim 1 wherein the fins include twisted shank blades and the peripheral extenions are parallel to the axial element.

3. A chalking device as in claim 1 wherein the fins include twisted shank blades, peripheral extensions parallel to the axial element and extended free ends inclined at a slight angle down from the peripheral extended portion and toward the next adjacent fins, the slight angle afforded between the adjacent fins serving to catch and hold an accumulation of powdered chalk as the rotary member is rotated through the chalk supply whereby chalking of the cord line is materially aided.

4. A chalking device as in claim 1, wherein the peripheral extensions of the fins include a plurality of scorings serving to catch and hold powdered chalk as the rotary member is rotated and further serving to enable gripping of the fins by the moving cord line.

5. A cord line chalking device comprising a circular container having a chamber adapted to hold a supply of powdered chalk, the container comprising a pair of opposed complementary circular shells, an axial element joining the opposed shells together, the shells being arranged in close relation to one another sufficiently to permit a cord line to be drawn between them, a rotary member carried within the chamber for rotatable movement on the axial element and including a plurality of twisted fins adapted to distribute the chalk supply about the chamber for contact with the cord line during rotation, extensions forming a peripheral surface at the ends of the fins adapted for contact with the cord line as it is drawn between the shells whereby the rotary member is caused to be rotated.

6. A cord line chalking device of the character described having a pair of separable opposed similar circular shells axially adjustable in relation to one another as to permit a cord line to be drawn between them and having a chamber formed by the opposed shells, the chamber including a supply of powdered chalk, a rotary member adapted for peripheral contact with the cord line and for rotation within the chamber as the cord line is drawn between the shells, whereby such rotation powdered chalk is

stirred about by the rotary member for contact with the cord line, and the shells each being provided with a flanged member having an annular trough containing a slightly extended band of soft material in opposed relation to one another, whereby contact is had with the opposed bands and the cord line when drawn between the shells.

7. In a chalking device as set forth in claim 6, wherein the shells are each characterized by a flat walled crown having a brim and a convexed annular shoulder between the crown and brim, whereby gripping of the device in the palm of the hand and with the thumb and forefinger thereof respectively in the annular shoulder of each crown is facilitated.

8. In a chalking device as in claim 6, wherein the rotary member is characterized by a plurality of radial fins twisted in the manner of a screw and having a peripheral surface adapted for contact with the cord line, whereby by such fins the chalk supply is readily picked up and carried toward the ends of the fins.

9. In a chalking device as set forth in claim 6, wherein the rotary member is characterized by a plurality of radial fins each having a peripheral surface parallel with the axis of the rotary member, a hub extending equally from each side of the rotary member whereby the peripheral fin surfaces are centered in the chamber between the shells.

10. In a chalking device as in claim 6, wherein the rotary member is characterized by a plurality of radial fins, each having a peripheral surface parallel with the axis of the rotary member and a portion extending down and away from the peripheral surface toward the next adjacent fin, whereby chalk stirred about by the rotary member when rotated is adapted to collect in a pile to insure a supply of chalk toward the ends of the fins for contact with the cord line.

11. In a chalking device as in claim 6, wherein the rotary member is characterized by a plurality of radial fins each having a peripheral surface parallel with the axis of the rotary member and a portion extending down and away from the peripheral surface toward the next adjacent fin but in a slightly spaced relationship thereto, whereby chalk stirred about by the rotary member when rotated is adapted to collect in a pile upon the extended portion to insure a supply of chalk to the peripheral surfaces of the fins for contact with the cord line, and whereby by such spaced relationship the chalk is adapted to filter down from the extended portions.

CHARLES SCUDDER.
